UNITED STATES PATENT OFFICE

LEWIS D. MATHIAS, OF NASHVILLE, TENNESSEE

DESIGN FOR A COMBINED DISPLAY RECEPTACLE AND INDIVIDUAL CONTAINER FOR TOILET PREPARATIONS

Application filed September 16, 1929. Serial No. 32,774. Term of patent 7 years.

To all whom it may concern:

Be it known that I, LEWIS D. MATHIAS, a citizen of the United States, residing at Nashville, in the county of Davidson and State of Tennessee, have invented a new, original, and ornamental Design for a Combined Display Receptacle and Individual Containers for Toilet Preparations, of which the following is a specification, reference being had to the accompanying drawing, forming a part thereof.

The figure in the drawing is a perspective view of the article showing my new design, consisting of a rectangular box-like base hav-

ing a plurality of connected triangular or diamond-shaped openings cut in the top wall thereof and triangularly shaped packets fitted into the openings in such a way as to form a grotesque figure or manikin said packets projecting above the surface of the base and containing toilet preparations such as bath salts, and/or toilet powder.

I claim:

The ornamental design for a combined display receptacle and individual containers for toilet preparations substantially as shown and described.

LEWIS D. MATHIAS.
